UNITED STATES PATENT OFFICE

PER BOTVID PERSSON, OF MALMO, SWEDEN

DISENGAGING GEAR FOR LIFEBOATS

Application filed July 16, 1929, Serial No. 378,719, and in Sweden July 21, 1928.

The present invention refers to disengaging gears for life boats of the kind consisting of turnable hooks which in a manner known in itself are provided with toothed segments 5 for coaction with slideable toothed racks or the like for turning the hooks, locking members normally preventing the displacement of said toothed racks in a direction for disengaging the hooks being simultaneously releasable by means of a common handle, so that the hooks at both ends of the boat may be simultaneously disengaged at the release of the locking members. The locking members are also combined with the toothed racks in 10 such a manner that the latter are displaceable by means of the former into a position for engaging the hooks with the tackle eyes carrying the boat. As the locking members are releasable by means of the handle irrespective 15 of whether the hooks are under influence of the weight of the manned boat or not, the disengagement of the hooks may be performed at any moment during the launching, even if the boat is not afloat on the water, if the hooks 20 are constructed in the manner specified below. This fact involves a very great advantage, as it permits the boat to be disengaged, for instance when not entirely lowered and lifted by the crest of a wave, so that the 25 severe stresses arising on the tackles when the wave falls again will be avoided. Further it is essential that the boat can be disengaged at any moment, for instance when the ship is 30 rolling on the seas and the life boat runs the risk of being crushed against the shell-plating of the former. Finally the life boat can also be disengaged when the ship is still steaming 35 ahead at a rather good speed, which is advantageous in case of rescue work of every kind. 40 According to the invention the hooks are disengaged from both of the tackles at exactly the same moment even if one end of the life boat should have been lowered more than the other, and the disengaging gear, when once released, cannot hook on again by itself. 45 Hereby the disadvantage is eliminated, that one or both of the tackle eyes, when hanging loose after the boat is afloat, can catch again 50 in case the boat should be further lowered by descending between two waves. Hence, it

will be apparent that the disengaging gear according to the invention involves a substantially higher degree of reliability than similar devices now in use, which in most cases cannot be disengaged until the life boat 55 is afloat and the load relieved from the tackles supporting the same.

A preferable embodiment of invention is shown in the accompanying drawing wherein

Fig. 1 shows an elevation of the disengaging gear, the thwart at the one end of the boat supporting the same being shown in vertical section.

Fig. 2 shows the disengaging gear seen from the under side of the thwart.

Generally it is to be remarked that a releasing gear of the kind shown in the drawing is intended to be at hand at each end of the life boat, both of such gears being manually operable by means of a common handle, 70 as will be described in the following.

The pivot pin 1 carries the hook 2 which is provided with a toothed segment 2^a placed in engagement with a toothed rack portion 3^a of a slideable rod 3, so that the hook will thus be turned when sliding the said rod. The rod 3 is preferably mounted on a plate 8 connected with a fork member 17 forming a bearing for the pin 1 and serving as a guide for the hook 2 in transverse direction, such fork member by means of a sturdy bolt 4 being affixed to the keel of the boat in a protected position beneath the thwart 6, which latter is provided with an aperture 6^a for inserting 80 the eye 5 or the like provided on the supporting tackle (not shown) and adapted for engagement with the hook 2 when desired.

In the embodiment of invention shown in Fig. 1 the construction of the hook 2 is of 90 such a kind that its supporting surface 2^b from the point of contact with the eye 5 has a slightly arc-shaped form upwardly. When the boat (and the load thereon) is supported by the eye 5, the tensional stress arising will have a component tending to turn the hook 2 in a direction for disengagement of the eye 5. In order to prevent such turning movement until desired, a locking member is provided, 95 100 which normally prevents the backward dis-

placement of the rod 3 until manually released.

In the embodiment shown the said locking member consists of a rockable arm 7 the end of which in the locking position is located in the path of travel of the end of the rod 3 remote from the hook 2, or else such arm could engage a recess in or coact with another abutment provided on the said bar. For steady- 10 ing the arm 7 in its locking position a guide slot is provided in the plate 8 so that the arm cannot yield for the pressure thereon from the rod 3 on account of the load on the hook.

By the means just described it will be apparent that an automatic disengagement will occur as soon as the arm 7 is manually reversed from the position shown (Fig. 2) so that the end of the rod 3 will be free, and therefore it will be possible to disengage the 20 life boat entirely independently of the weight of the boat and the load thereon. This embodiment is therefore the preferred one.

It will also be possible, however, to give the supporting face of the hook 2 the shape shown 25 by the dotted line 2^a in Fig. 1. Hereby the overhanging end of the hook is curved downwardly from the point of contact with the eye 5, and thus it will be self-locking so that a disengagement of the same must be performed by forcibly turning the hook by sliding the rod 3. If the point of the hook has a sufficiently low position, it may happen that the locking action will be so strong that a 30 manual disengagement cannot be performed unless the load is relieved from the eye 5, i. e. unless the boat is afloat on the water. In certain cases a constructional modification of this kind will perhaps be desired, but in case of life boats for seagoing vessels the first embodiment described above no doubt is to be preferred, especially if a skilled crew is accessible.

In respect of both of the embodiments of invention described above it is desirable or necessary that the rod 3 can be manually displaced by means of a handle 10 preferably affixed to a shaft 9 extending in the direction of length of the boat along the keel of the same, such shaft at each end being provided with 50 an arm 7 of the kind described above.

According to the invention the displacement of the rods 3 can be performed by means of the handle 10 by the intermediary of the arms 7 and a fork-shaped plate 12 pivotally mounted on a pin 11 affixed to the plate 8. The plate 12 is provided with a recess 13 for coaction with the free end of the arm 7, and the rod 3 is provided with a bolt 14 penetrating an oblong slot 15 in the plate 12, such 60 slot having a shape so as to permit the turning of the plate simultaneously with the displacement of the rod 3 and the toothed rack portion of the same. The plate 8 is also provided with a slot 16 penetrated by the bolt 14, 70 which is slidable in said slot.

In the drawing the mechanism is shown in a position for supporting the boat, the mechanism being locked. Supposing that an actuation of the handle 10 causes a turning of the arm 7 from the position shown, the upper end of the same (see Fig. 2) will at first be drawn away from the end of the rod 3 and take a position opposite to the recess 13 in the plate 12. Now, in case the hook 2 is of the automatically disengaging type described above, 75 no further manipulation is required for disengaging the boat, the weight of the boat and the load being sufficient for instantaneously pushing back the rod 3, the hook turning simultaneously and releasing the eye 5. 80

On the contrary, if the hook 2 is of the automatically locking type referred to above, the turning of the arm 7 will at first result in nothing, but the gear is ready for disengagement of the boat from its tackles by a further pull in the handle 10, as soon as the boat is afloat. At a manual disengagement of this kind the arm 7 now located in the recess 13 is turned further. Thereby it strikes the opposite side of the recess and causes a turning movement of the plate 12 which latter by means of the constructional parts described above positively displaces the rod 3 in a direction for disengaging the boat. As both of the hooks mounted at the respective ends of the boat are combined by means of the shaft 9, the disengagement is simultaneous at both ends. It is apparent that the hooks 2 by means of the handle 10 may also be turned back into their normal working position, and thereafter they are locked by means of the arm 7 then taking the position shown in the drawing. The handle 10 may suitably be combined with sealing means (string and lead seal) when in the locking 95 position, so that the seal must be broken at the manipulation of the mechanism.

What I claim and desire to secure by Letters Patent is:

1. A disengaging gear for life boats comprising at each end of the boat, a turnable hook member, a toothed segment connected therewith, a slidable toothed rack member engaging said segment, locking means coacting with said rack member and normally preventing the displacement of the same into a hook releasing position, means for simultaneous release of said locking means at both ends of the boat, and means for positively displacing the rack member into a hook releasing position after release of the locking means.

2. A disengaging gear for life boats comprising, a turnable hook member at each end of the boat, a toothed segment connected with each hook, a slidable toothed rack member engaging each segment, locking means coacting with each rack member and normally preventing the displacement of the same into a hook releasing position, a common connect-

ing means connecting the locking means at both ends of the boat, a handle means connected with said connecting means, and means for positively displacing the rack members 5 into a hook releasing position, such last-mentioned means being combined with the said locking means and acted upon by the latter in such a manner, that after a release of the locking means a continued movement of the 10 same will positively displace the hook members into a release position.

3. A disengaging gear for life boats according to claim 2, characterized in that the connecting means between the locking means 15 at both ends of the boat consists of a turnable shaft mounted longitudinally in the boat and connected with a handle bar.

4. A disengaging gear for life boats comprising, a turnable hook member at each end 20 of the boat, a toothed segment connected with each hook, a slidable toothed rack member engaging each segment, a shaft mounted longitudinally in the boat and provided for each toothed rack member with a locking 25 arm normally taking a position in the path of travel of said rack member for preventing the hook to be turned into a release position, handle means connected with said shaft for turning of the same, and means actuated by 30 the locking arms for positively displacing the hooks into a release portion after the said arms have been moved out of the path of travel of the toothed rack members.

5. A disengaging gear for life boats comprising at each end of the boat, a turnable hook member, a toothed segment connected therewith, a slidable toothed rack member engaging said segment, a turnable locking arm normally located in the path of travel 40 of said rack member so as to prevent the rack member to be slid into a hook releasing position, means for turning of said locking arm, a turnable connection member between the locking arm and the toothed rack, 45 a recess in said connection member adapted to take up the end of the locking arm, and means for pivotally connecting the connection member with the toothed rack member in a manner so that the latter may be slid 50 by the turning movement of the former when acted upon by the locking arm.

In testimony whereof I have signed my name to this specification.

PER BOTVID PERSSON.
